UNITED STATES PATENT OFFICE.

FRANK E. FISHER, OF DETROIT, MICHIGAN, ASSIGNOR TO THE MERCHANTS STORE RAILWAY COMPANY, OF SAME PLACE.

STORE-SERVICE TRACK.

SPECIFICATION forming part of Letters Patent No. 355,604, dated January 4, 1887.

Application filed January 11, 1886. Serial No. 188,240. (No model.)

To all whom it may concern:

Be it known that I, FRANK E. FISHER, of Detroit, in the county of Wayne and State of Michigan, have invented a new and useful Improvement in Store-Service Railway-Tracks, 5 of which the following is a specification.

My invention consists in an improvement in tracks for store-service railways, hereinafter fully pointed out and claimed.

10 Figures 1 and 3 are side elevations, and Fig. 2 a plan view, of a portion of my improved track.

In operating store-service railways of the class in which a car is propelled over a track 15 either of stretched wire or metal strip, it is often desirable to put a curve in the track. To give a car sufficient initial velocity to round a curve at a distance from the starting-point and then travel beyond the curve necessitates

20 too high momentum at the start, although it can readily be done with the mechanism shown in my application for a patent filed October 12, 1885, Serial No. 179,707; but in so doing there is always danger of displacing the

25 car from the violent impetus necessary. To obviate this difficulty I place at any desired point in the track a laterally-extending curve, 9, properly braced, and make said curved portion the highest point in the track, inclining the track both ways from said curve, unless said curve should be at one end of the track.

1 and 2 represent two portions of a store-service railway-track, which may be made of 30 a stretched wire or of a metal strip.

9 represents a laterally-extending curve in the track, its ends being connected with the track 1 2, and this curve is stayed in any suitable manner, the mode shown in the drawings 40 being by two guy-wires, 7 and 8, running to any convenient support, to counteract the strain of the wire track 1 and 2, and a suspending-wire, 3. In some cases it is also de-

sirable to fasten the angle-piece 4 5 to the ends of the curve 9, and to run a stay-bolt, 6, 45 from the angle to the curve.

The curve 9 is the highest point in the track, the wires 12 descending from the curve to the terminal stations. In the arrangement shown in Fig. 1 the sides of the curve are inclined at the same angle as the wires 1 and 2, the apex of the track being at the center of the curve, as shown by the dotted line 10. In the arrangement shown in Fig. 3 the curve is level, or substantially so, and only the wires 1 50 and 2 are inclined. By this arrangement the car starting from the terminal station of wire 1 need only be given sufficient momentum to carry it around the curve 9, when it will descend wire 2 by gravity, and vice versa. 55

What I claim as my invention, and desire to secure by Letters Patent, is—

1. In a store-service railway-track of the class in which a car is propelled over the track, a laterally-extending curve located at 65 the highest point of said track, substantially as shown and described.

2. In a store-service railway-track of the class in which a car is propelled over the track, a lateral curved portion, suitably stayed, and 70 a straight portion inclining downward from said curved portion, substantially as shown and described.

3. In a store-service railway-track of the class in which a car is propelled over the track, 75 a track consisting of two stretched wires at an angle with each other, each inclined upwardly from their terminal stations, and a lateral curved track connecting said stretched wires at their highest points, substantially as shown 80 and described.

FRANK E. FISHER.
